VACUUM CLEANER OR SIMILAR ARTICLE

William Balla, Dearborn, Mich., assignor to General
Electric Company, a corporation of New York

Application October 25, 1956, Serial No. 43,532

Term of patent 14 years

(Cl. D9—2)

Fig. 1.

Fig. 2.

Des. 182,638

PAGE 2

Fig. 3.

Fig. 4.

Fig. 5.

Fig. 6.

Fig. 1 is a rear elevational view of the vacuum cleaner or similar article embodying the new design.

Fig. 2 is a top plan view thereof.

Fig. 3 is a front elevational view thereof.

Fig. 4 is a bottom plan view thereof.

Fig. 5 is a side elevational view thereof.

Fig. 6 is a perspective view showing the rear, side and top thereof.

The side of the vacuum cleaner which is opposite to the one shown in Fig. 5 is substantially the same in appearance as the side shown in Fig. 5.

I claim:

The ornamental design for a vacuum cleaner or similar article, substantially as shown and described.
